(57) **CLAIM**

The ornamental design for a back support brace, as shown and described.

DESCRIPTION

FIG. 1 is a front elevation of a back support brace showing the new design;

FIG. 2 is a back elevation view thereof;

FIG. 3 is a left-side view thereof;

FIG. 4 is a right-side view thereof;

FIG. 5 is a top plan view thereof; and

FIG. 6 is a bottom plan view thereof.

FIG. 7 is a perspective view thereof;

FIG. 8 is another perspective view thereof;

FIG. 9 is a perspective view of the back support brace of FIG. 1, shown in condition of use for clarity of disclosure;

FIG. 10 is an enlarged view of the encircled portion in FIG. 5; and,

FIG. 11 is an enlarged view of the encircled portion in FIG. 9.

The broken lines of FIG. 9 depicting a human body represent environmental structure that forms no part of the claimed design.

The dash-dot lines in FIGS. 5, 9, 10, and 11 illustrate the boundaries of the enlarged view indicators and form no part of the claimed design.

1 Claim, 11 Drawing Sheets
